UNITED STATES PATENT OFFICE.

CHARLES HAVELOCK TAYLOR, OF TORONTO, ONTARIO, CANADA.

THREAD-CUTTER.

1,276,445.

Specification of Letters Patent. Patented Aug. 20, 1918.

Application filed March 9, 1916. Serial No. 83,104.

To all whom it may concern:

Be it known that I, CHARLES HAVELOCK TAYLOR, of the city of Toronto, Province of Ontario, Dominion of Canada, have invented 5 certain new and useful Improvements in Thread-Cutters, and the following is a full, clear, and exact description of the same.

My invention relates particularly to automatic machines and has for its object to provide an attachment for machines of this type; whereby a thread may be cut either even with the perimeter of the work or behind a shoulder, a feature of the invention being that the thread may be cut before the 15 piece is separated from the stock and the thread commences immediately at the face of the shoulder. Another feature of the invention is that a thread may be cut on the reduced diameter between the ends of the bar 20 either to receive a split nut or be subsequently divided and form the screw threaded ends of separate pieces.

Broadly stated, my invention consists of a unitary rotary tool of circular form with its 25 perimeter divided into a plurality of threads each thread being divided into a plurality of cutting teeth. The number of these cutting threads in the embodiment illustrated is not an aliquot part of the number of teeth 30 in each thread. The threads are spaced uniformly around the circumference of the tool, but as the number of threads does not divide the number of teeth in each thread evenly, the teeth will not be in lines parallel 35 to the axis of the tool but in oblique lines, the angle of obliquity depending upon the number of teeth in each thread and the lead of the thread. This tool is, as before mentioned, rotary, and it is combined with a 40 chuck, or other stock holding means, also having rotation imparted to it, and the relative speed of the tool and stock is an important factor. The stock must be driven at as many times greater speed than the 45 tool as there are threads on the tool, the effect being that one continuous thread is cut on the stock equal in length to the width of the tool and possessing a lead equal to a fraction the thread of the tool is of its lead. 50 I have illustrated and will describe my invention applied to an automatic machine having a collet for holding the stock and

feeding mechanism by which the stock is intermittently fed through the collet, and a pair of alternating cross slides carrying respectively my improved cutting tool and a cutter for separating the finished piece from the stock.

For full comprehension, however, c my invention reference must be had to the accompanying drawings in which similar reference characters indicate the same parts, and wherein,

Figure 1 is a transverse sectional view of a machine of the type mentioned and 65 equipped with my invention;

Figs. 2 and 3 are side elevations of my improved cutter removed;

Figs. 4 and 5 are detail views of the thread milling cutter removed and drawn to a 70 larger scale, the cutter being illustrated in process of manufacture with the threads formed on the perimeter and partially toothed;

Fig. 6 is a sectional view of the annular 75 member upon which the cutter is mounted;

Fig. 7 is an elevation of a portion of a lathe for carrying my improved attachment and illustrating the attachment in vertical section;

Fig. 8 is a plan view of the attachment;

Fig. 9 is a diagonal sectional view taken on line 9-9 Fig. 7;

Fig. 10 is a diagram of the gears for obtaining the required relative milling speeds 85 of the cutter and stock;

Fig. 11 is a detail end elevation of the head and driving mechanism for the attachment; and

Fig. 12 is a plan view thereof.

The frame of the automatic machine to which my invention is applied is indicated at 2, the cross slides at 3 and 4, the collet at 5, the cams for operating the slides at 6 and 7 and the levers effecting the operative connection between the cams and slides at 9 and 10 and 11.

My improved thread cutter has a milling action and it is incorporated in an attachment mounted upon slide 3 and the cutter 100 by which the finished piece is separated from the stock is carried by an attachment 16 mounted rigidly on a slide 4.

In the present application of my inven-

tion my milling screw cutter consists of an annular member 20 although for other requirements the particular form may be changed, the milling face being the essential 5 feature. This milling face or perimeter is cut to present six independent and separate threads, 21, 22, 23, 24, 25, and 26 respectively, each thread being cut to present a plurality of teeth as illustrated in Fig. 4. 10 These threads commence at one end or side of the cutter at intervals of one-sixth the circumference and extend parallel around the cutter finishing at the other end or side. They have corresponding leads and each lead 15 is approximately the axial length of the milling face.

In order to present the oblique arrangement of teeth across the face of the cutter, I cut each of the threads into 71 teeth, thus 20 securing a spacing between the initial ends of the threads of $11\frac{5}{6}$ teeth. That is to say the second thread starts $11\frac{5}{6}$ teeth from the start of the first thread and consequently the teeth of the second thread will be $\frac{1}{6}$ of a 25 tooth in advance of the teeth of the first.

In order to obtain correct relative speeds of the stock and milling cutter I have designed a special attachment including the necessary gears and carrying the annular member 30 which has the milling face above described cut upon its perimeter, and I will now describe this attachment. It consists of a pair of frames 30 and 31 which are left and right halves respectively. The left half of the 35 frame has a rib 32 which engages a corresponding groove in the cross-slide 3 to which it is fastened by bolts or screws. The right half 31, is bolted to and carried by the left half and between them is mounted an internal gear 35, one end of which is of reduced 40 diameter, 36, and cut with a left hand thread. This end of the internal gear has screwed thereon the annular milling cutter, the cutting face of which protrudes from the forward face 37 of the attachment. This internal gear is driven from a chuck or main 45 driving gear 40 of the machine which gear is driven in the direction indicated and drives a pinion 41 upon the shaft of which a second 50 pinion 42 is also rigidly mounted. This latter pinion is the driven element with which the driving gear of the attachment come into operative engagement when the cross slide 3 is moved to an operating position. The 55 gears of the attachment consist of the internal gear 35 and a train of gears 43, 44 and 45, the latter being mounted rigidly upon a shaft upon which is also rigidly mounted a gear 47 adapted to come into mesh with gear 42 when the slide is shifted to operating position. This system of gearing is adapted to 60 impart to the milling cutter a speed of one revolution to six revolutions of the stock and as it is an important factor that these

relative speeds be obtained, I will describe 65 the gears specifically in tabulated form:

Gear.	Teeth.	Pitch.	Pitch diam.	Out diam.
40-41	73	20	3,650	3,750
42	21	20	1,050	1,150
43	42	20	2,100	2,200
45	16	14	1,143	1,286
35	48	14	3,249	{ 3,572 3,286 inside.

As this invention relates only to the milling of the screw-thread and rotation of the stock in coaction with the milling operation, and as the means for advancing the stock after each milling and severing operation may be of any of the well known types of stock feeding devices, I have neither described nor illustrated the latter; but it will be understood nevertheless that the stock is advanced as required after each threading and severing operation.

The finished piece is severed from the stock by a cutting tool 50 mounted in a carrier 51 fastened rigidly to the slide 4.

Operation.

During the milling operation the toothed cutter and stock rotate in the same direction and their contacting faces rotate in opposite directions, and as the stock makes six revolutions to one of the toothed cutter a continuous screw thread is cut in the perimeter of the stock having a lead one sixth the lead of the cutter and equal in length to the axial length of the face of the cutter.

In order to produce a double, triple or quadruple thread, the driving gears should be changed to run the cutter one-third, a half or two-thirds the number of revolutions of the stock.

The greater number of teeth on the cutter with proportionately less number of revolutions of the cutter, the more perfect the edge of the thread milled, and the fewer the number, the rougher the edge, while the number of threads govern the speed of both the cutter and stock which may be varied, to give the proper cutting speed.

From the foregoing it will be seen that my improved milling cutter is essentially of helical form and performs its function without axial movement of either the cutter or the stock, and the multiple quality of the cutter may be increased or diminished without departing from the spirit of my invention.

What I claim is as follows:

1. In a milling screw-cutting attachment for an automatic screw machine a frame adapted to be incorporated in the machine, an internal gear mounted in the frame an annular cutting member mounted upon said gear and means for driving the gear.
2. A milling screw cutter having an even

- number of toothed helical threads and each thread having an odd number of teeth.
3. A milling screw cutter having an even number of toothed helical threads uniformly spaced around the periphery of the cutter and each thread having an odd number of teeth.
4. A milling screw-cutter having toothed helical multiple threads uniformly spaced around the periphery of the cutter, the threads having corresponding number of teeth and the number of threads being an aliquant part of the number of teeth of each thread.
15. 5. The combination with a screw-cutting machine frame and a rotary stock-holding collet, of a milling screw-cutter having toothed helical multiple threads uniformly spaced around the periphery of the cutter the threads having corresponding number of teeth and the number of threads being an aliquant part of the number of teeth of each thread, and means rotatively connecting the collet and cutter whereby the latter is rotated a fraction of the revolutions of the collet equal to number of threads into which the lead of the cutter is divided.
6. A milling screw cutting attachment for an automatic screw machine, comprising a frame adapted to be incorporated in the machine, a gear rotatably mounted in the frame; an annular member rigidly mounted upon the gear and having toothed multiple threads and the number of threads being an aliquant part of the number of teeth of each thread; a driving gear rotatably mounted in the frame; and a train of gears rotatively connecting the driving gear to the internal gear.
40. 7. A milling screw-cutting attachment for an automatic screw machine, comprising a frame adapted to be incorporated in the machine, a gear rotatably mounted in the frame; a helical milling screw-cutting member rigidly mounted upon the gear; a driving gear rotatably mounted in the frame; and a train of gears rotatively connecting the driving gear to the first mentioned gear.
8. In a screw cutting machine a milling screw-cutter, means for rotating said cutter, and a continuously rotating mechanism for driving said means, such means being normally in operative engagement with said mechanism and adapted to be moved out of engagement therewith.
50. 9. In a screw-cutting machine, the combination with a rotary stock carrier and a slide, of a milling screw-cutting attachment comprising a frame mounted upon the slide;
- an annular member rotatably mounted upon said frame, the perimeter of said member having uniformly circumferentially spaced toothed multiple peripheral threads, means for rotating said annular member, said means including an internal gear, and gears adapted to impart rotation to the internal gear when the slide is shifted.
10. In a screw-cutting machine, the combination with a rotary stock carrier, a tool-driving gear in rotative relation therewith, and a pair of cross-slides with means for reciprocating the same, of a milling screw-cutting attachment comprising a frame, means fastening the frame to one of the cross-slides; a cylindrical member rotatably bearing within the frame and having internal gear teeth; an annular member mounted rigidly upon one end of the cylindrical member with a portion of its outer perimeter protruding beyond the frame, and the said perimeter having uniformly circumferentially spaced toothed multiple peripheral threads; a driven gear rotatably mounted within the frame and arranged to engage the said tool-driving gear when the slide is shifted in one direction; and a train of gears rotatively connecting the driven gear to the internal gear.
15. 11. In a screw-cutting machine, the combination with a rotary stock-carrier, a tool-driving gear in rotative relation therewith, and a pair of cross-slides with means for reciprocating the same, of a milling screw-cutting attachment comprising a frame, means fastening the frame to one of the cross-slides; a cylindrical member rotatably bearing within the frame and having internal gear teeth; an annular member mounted rigidly upon one end of the cylindrical member with a portion of its outer perimeter protruding beyond the frame and the said perimeter having uniformly circumferentially spaced toothed multiple peripheral threads; a driven gear rotatably mounted within the frame and arranged to engage the said tool-driving gear when the slide is shifted in one direction; a train of gears rotatively connecting the driven gear to the internal gear; and a cutting tool mounted on the other slide and arranged to sever.

In testimony whereof I have signed my name to this specification in the presence of two witnesses.

CHARLES HAVELOCK TAYLOR.
